UNITED STATES PATENT OFFICE.

SAMUEL P. WILLEBY, OF PHILADELPHIA, PENNSYLVANIA.

HOISTING STORM-SAILS.

SPECIFICATION forming part of Letters Patent No. 226,142, dated March 30, 1880.

Application filed January 15, 1880.

To all whom it may concern:

Be it known that I, SAMUEL P. WILLEBY, of Philadelphia, in the county of Philadelphia and State of Pennsylvania, have invented 5 certain new and useful Improvements in Hoisting Storm-Sails; and I do hereby declare the following to be a full, clear, and exact description of the invention, such as will enable others skilled in the art to which it pertains 10 to make and use it, reference being had to the accompanying drawings, which form part of this specification, in which—

Figure 1 is a side elevation of my invention; Figs. 2 and 3, detail perspectives, and 15 Fig. 4 an enlarged front elevation of the wire-rope stay and its fastening devices.

My invention has for its object to provide means whereby the storm try-sails of fore-and-aft-rigged vessels may be hoisted with greater 20 ease and facility and in less time than heretofore.

My invention consists in the combination, with the try-sail provided with suitable hanks, of a laterally-movable stay-rod, upon which 25 said hanks slide, and a band secured to the mast and having a segmental rod or traveler, upon which moves an eye or ring attached to the stay-rod, as and for the purpose hereinafter described.

30 Referring to the annexed drawings, A indicates a fore-and-aft-rigged vessel, and B one of its masts. C is a storm try-sail, to the luff of which is fastened, at suitable intervals, hanks c c.

35 D is a stay of any suitable material, preferably wire-rope, located just aft of the mast, its lower end being made fast to the deck by means of an eye, d', its upper end having a shackle or equivalent device, d, whereby it 40 can be properly secured, and at the same time permitted movement, as hereinafter set forth.

E is a band similar to or may be the futtock-band, located just below the trestle-trees F F'. To this band is secured a segmental 45 rail or traveler-rod, G, on which the shackle d can freely slide from side to side of the mast.

From the cross-trees F' hangs a throat-block, H, through which pass the halyards I. In practice it is designed to use two blocks, 50 so as to obtain greater power, although I have illustrated only one, and I design also providing a pair of blocks between the lower end of the stay and the deck, so as to draw said stay taut.

In very fair weather, or when storm-sails 55 are not likely to be required, it will not be necessary to have the stay in position, and then it may be down and stowed away with the try-sail. In stormy weather, or at seasons when storm-sails are likely to be required, the 60 stay should be kept up in position, the try-sail being kept reefed until required to be hoisted.

When necessary to hoist the try-sail all that will be required is to haul upon the halyards, the hanks sliding freely on the stay, and after 65 the sail is hoisted make the halyards fast to the cleat K, the block H bringing the peak of the sail amidships.

When the try-sail is taken down the stay D may be permitted to remain up, and will not 70 interfere with the mainsail or its gaff, as the traveler rail or rod G will permit such stay to swing to either side of the mast out of the way of the mainsail or gaff.

The great advantage of this improvement 75 lies in the facility and speed with which a storm try-sail by its employment can be hoisted and set.

Hitherto the beackets employed had each one to be brought around the mast in succession 80 and tied—a work of considerable difficulty and requiring no little time. So, too, as the beackets surround the mast and slide thereon, and as the mast is not unfrequently sticky and dirty, it is frequently very laborious to cause 85 the beackets to move over it. By the employment of the stay and hanks, however, the beackets are dispensed with and the encircling and sliding upon the mast avoided.

The hanks move freely on the stay and the 90 latter is not in the way of the mainsail or its gaff when hoisted, as it is capable of being easily moved to either side of the mast on the traveler-rod.

What I claim as my invention is— 95

The combination, with the stay D, try-sail C, having the hanks c, and band E, of the segmental rod or traveler G, whereby said stay is capable of being moved to either side of the mast to avoid the mainsail or its gaff, substantially as specified. 100

In testimony that I claim the foregoing I have hereunto set my hand this 12th day of January, 1880.

SAMUEL P. WILLEBY.
